(57) **CLAIM**

The ornamental design for a curved shower bar, as shown and described.

DESCRIPTION

FIG. 1 is a front perspective view of the curved shower bar in accordance with the present invention; FIG. 2 is a right side cross-section view thereof, the left side cross-section view being the mirror image thereof; and, FIG. 3 is a top view thereof.

The dashed line showing the bathtub stall walls, bathtub, shower curtain, and shower curtain rings in FIGS. 1-3 are shown for illustrative purposes only and form no part of the claimed design.
